CLAIM

The ornamental design for a a liposuction fat collection canister, as shown and described.

DESCRIPTION

FIG. 1 is a front perspective view of a liposuction fat collection canister showing my new design;
 FIG. 2 is a rear perspective view thereof;
 FIG. 3 is a right elevation view thereof;
 FIG. 4 is a front elevation view thereof;
 FIG. 5 is a left elevation view thereof;
 FIG. 6 is a rear elevation view thereof;
 FIG. 7 is a top plan view thereof; and,
 FIG. 8 is a bottom elevation view thereof.
 The broken lines show portions of the design that form no part of the claimed design.
